UNITED STATES PATENT OFFICE.

FREDERICK SARGENT, OF CHICAGO, ILLINOIS, AND DAVID S. JACOBUS, OF JERSEY CITY, NEW JERSEY, ASSIGNEES TO THE BABCOCK & WILCOX COMPANY, OF BAYONNE, NEW JERSEY, A CORPORATION OF NEW JERSEY.

BOILER-ECONOMIZER.

1,048,739.

Specification of Letters Patent. Patented Dec. 31, 1912.

Application filed July 16, 1912. Serial No. 709,774.

To all whom it may concern:

Be it known that we, FREDERICK SARGENT, a citizen of the United States, and a resident of Chicago, in the county of Cook and 5 State of Illinois, and DAVID S. JACOBUS, a citizen of the United States, and a resident of Jersey City, in the county of Hudson and State of New Jersey, have invented certain 10 new and useful Improvements in Boiler-Economizers, of which the following is a specification.

The purpose of an economizer is to pre-heat the boiler feed water, or to heat water for other purposes, and is placed in the flue 15 between the boiler, or other source of waste heat, and the stack; that is, an economizer is used to recover from the gases of combustion, heat that would otherwise escape through the stack. An economizer in reality forms an extension of the heating surface proper, but it is more effective for the transfer of heat than the last pass of the boiler heating surface, because of the lower temperature of the contents; it being well-known that boiler surface does not extract 20 heat from the gases once they have approached a temperature corresponding to the steam pressure in the boiler.

The advantages of an economizer in utilizing the heat of the escaping gases are well-known; but in its development it has been ascertained that increasing the velocity of a given weight of gases in making them flow over a given amount of surface, 35 increases the heat transfer rate and the efficiency. To utilize this principle, the gases must be given a long travel over the economizer tubes either by the use of baffles for contracting the cross sectional area of the 40 path of the gases, or by the use of a relatively long and narrow economizer. For a minimum draft resistance the best results are obtained by the use of a long and narrow economizer, as the gases then travel in a 45 straight path through the economizer and the resistance of turns and bends in the path of the gases is eliminated. In modern power plant practice, where economy of floor space is an important item, it is practically impossible to install economizers to advantage 50 of a length sufficient to give the best heat transfer results if it were attempted to do this in the ordinary way.

The object of the present invention there-

fore, is to provide a means whereby the advantages attaching to a long and narrow economizer may be attained where economy of floor space is a desideratum.

In carrying out our invention we place the economizers in pairs above and transversely 60 of the boilers, and the gases from two boilers are made to pass in opposite directions through the economizers and thence to exhaust fans, from which they are discharged 65 through flues leading to the stack.

The invention will be understood by reference to the accompanying drawings in which—

Figure 1 is a side view of a boiler setting having our arrangement of economizers; 70 Fig. 2, a top view; and Fig. 3, a front view.

We have shown in the drawings a pair of boilers spaced apart. In a plant having more than two boilers they would be arranged in two lines in pairs, a pair constituting a unit, and as they are similar in construction and arrangement it will only be necessary to refer to one pair. Each unit comprises two boilers 1 and 2, the boilers being set back to back as shown in the drawings although this is not essential, that is, the firing doors may be at the front, rear or sides as may be desired in any particular installation. Again, the boilers may be set so that there is no space between them. 85 Placed side by side above and transversely of the boilers and spanning any space that may be left between them, are two economizers 3 and 4. The waste gases from boiler 2 pass upward through a flue 5 to the economizer inlet, thence through the economizer 3 to a fan 6 at a point above the front of boiler 1, from which they are discharged 90 into a flue 7 and finally into the stack 9 through a connecting flue 8. The gases from boiler 1 pass upward through a flue 10, thence through economizer 4 to a fan 11 at a point above the front of boiler 2, from which they 95 are discharged into a flue 12 and pass through a connecting flue 13 to stack 9. 100

With the arrangement above proposed it is possible to have a compact and effective economizer arrangement with a minimum amount of floor space. The gases are led through the economizers in opposite directions with a minimum number of turns, and may be discharged from the fans into the flues 7 and 12 in the direction in which they

travel in the said flues, so that there is no undue loss through not utilizing the velocity of the gases imparted by the fans, the fans being placed directly under said flues.

5 It is possible, as shown by the drawings, to install a series of economizers in the way indicated and maintain the advantages secured in a single unit.

What we claim is:—

10 1. A boiler unit comprising two boilers spaced apart, an economizer for each boiler placed above and spanning the boilers, and flues for conducting the gases from the boilers to the economizers, and from the 15 economizers to a common stack.

2. A boiler unit comprising two boilers, an economizer for each boiler placed above and spanning the boilers, and flues for directing the gases from the boilers through 20 the economizers in opposite directions and from the economizers to a common stack.

3. A boiler unit comprising two boilers, an economizer for each boiler placed above and spanning the boilers, flues connecting 25 each boiler with its economizer, a fan at the outlet of each economizer, and flues from the fans to a common stack.

4. A boiler unit comprising two boilers, an economizer for each boiler placed above 30 and transversely of the boilers and spanning them, and flues connecting each boiler with its economizer so as to cause the gases to travel the economizers in opposite directions.

5. A boiler unit comprising two boilers, 35 an economizer for each boiler placed above and transversely of the boilers and spanning them, flues connecting each boiler with its economizer, the outlet of each economizer being at a point above the other boiler, flues 40 into which the gases discharge from the

economizers, said discharge flues directing the gases to a common stack in the direction in which they travel in the flues.

6. A boiler unit comprising two boilers, 45 an economizer for each boiler placed above and transversely of the boilers and spanning them, flues connecting each boiler with its economizer, the outlet of each economizer being at a point above the other boiler, flues into which the gases discharge from the economizers, a fan in each of the discharge flues, said fans forcing the gases to a common stack in the direction in which they travel in the flues.

7. A boiler unit comprising two boilers, 55 an economizer for each boiler placed above and spanning the boilers, and flues for conducting the gases from the boilers to the economizers, and from thence to a stack.

8. A boiler unit comprising two boilers, 60 an economizer for each boiler placed above and spanning the boilers, flues for conducting the gases from the boilers to the economizers, a fan attached to the discharge flue of each economizer, said fans forcing the 65 gases to flues leading to a stack in the same general direction in which they travel in the flues.

In testimony whereof we have hereunto signed our names in the presence of two sub- 70 scribing witnesses.
